(57) CLAIM

The ornamental design for a cosmetic container, as shown and described.

DESCRIPTION

FIG. 1 is a perspective view of the container according to the design;

FIG. 2 is a top plan view thereof;

FIG. 3 is an elevational view of the left or right side of FIG. 1; and,

FIG. 4 is an elevational view of the front or rear of FIG. 1. The dotted lines on the drawing represent the interior outlines of the design visible through translucent surfaces.
